FLUID DISTRIBUTION SYSTEM

Alan T. Chapman, North Caldwell, N.J., assignor to Western Electric Company, Incorporated, a corporation of New York

Filed Feb. 8, 1961, Ser. No. 87,896
16 Claims. (Cl. 137—624)

This invention relates to a fluid distribution system and particularly to a digitalized distributor for fluid media.

In pneumatic or hydraulic systems, definite pressures or volumes are required to obtain certain desired effects such as a predetermined translational movement of a member or the attainment of a predetermined compression in a confined space. It is especially desirable in view of the continuing trend toward the adoption of automation to obtain such results in accordance with a computer arrangement, for instance, by means of punched cards or perforated tapes containing digital coded information or directly by means of a selector mechanism providing similar information.

An object of the present invention is a fluid distribution system for distributing fluid in response to information available in digital form.

One aspect of the invention relates to a distributor for a fluid media for moving a member to predetermined positions in accordance with information provided in digital form.

Another aspect of the invention relates to controlling the fluid input and output of a fluid distribution system in such a manner as to assure accuracy in the distribution of the fluid.

Additionally, the present digital fluid distribution system may allow for the inertia of the system, such as, the mass of moving parts, to attain accuracy in the positioning of a member.

In carrying out the invention, fluid from a source is passed through a distributor system including a series of inlet ports and preferably a series of outlet ports arranged in coded form to allow predetermined amounts of fluid to be conveyed to a desired location.

In one embodiment, a work positioning cylinder is controlled by digitalized amounts of fluid supplied through selected ones of a plurality of channels or openings related to each other on a decimal or binary basis. The channel selection may be effected by means of an assembly of discrete members, one of which may be rotated to bring desired channels into registration for predetermined times to pass definite amounts of fluid from a source to the work positioning cylinder to move the cylinder rod to a predetermined position. An exhaust arrangement is provided to return the fluid from the cylinder after it has served its purpose.

The invention will be better understood by reference to the following detailed description and to the drawings, wherein:

FIG. 1 is a sectional view of the fluid distribution system, together with a schematic representation of a servomotor and control apparatus therefor;

FIG. 2 is an end view of a coded disc used in the present application;

FIG. 3 is an end view of a distributor disc used in the present invention;

FIG. 4 is a modification of the invention showing a different arrangement of the coded disc;

FIG. 5 is a fragmentary view showing the crossover of coded openings in the modification;

FIG. 6 is a view taken along the line 6—6 of FIG. 5, and;

FIG. 7 shows a modification of a distributor device for use with the coded disc shown in FIGS. 4, 5 and 6.

One embodiment of the invention as shown in FIGS. 1,

2

2 and 3, includes a fluid distribution system 51 for controlling the positioning of rod 52 within the cylinder 53. The distribution system includes four discs 54, 55, 56 and 57, of which, discs 54, 56 and 57 are fixed and disc 55 is rotatable by means of the servomotor 58. It will be observed that disc 55 is fixed to the shaft 59 by means of the pin 61. The servomotor 58 is operated in response to information received from the control apparatus 62 which may include, for example, a tape or card reader and a digital-to-analog converter for controlling the servomotor 58.

Disc 54 comprises two concentric channel-shaped rings 63 and 64, the outer ring 63 providing a source of fluid under pressure received over line 67 while the inner ring 64 provides a fluid return chamber which enables the fluid to return via line 68 to storage conveniently, but not necessarily, at atmospheric pressure.

Disc 55 is a rotatable fluid distributor and, as shown in FIGS. 1 and 3, is solid except for the L-shaped openings 71 and 72. Opening 71 leads to the inner ring 64 of disc 54 and the diametrically opposite opening 72 leads to the outer ring 63 of disc 54.

Coded disc 56 includes an outer ring section 77 and an inner ring section 80. Coded openings or channels 0-1 to 0-34 provided in the ring sections, have diameters arranged in accordance with a digital code, the openings being selectively opened and closed by the lower face of distributor 55 as viewed in FIG. 1. Thirty-six positions on disc 56 have been shown in FIG. 2 for convenience in description. While in some instances, two coded openings of different diameter are shown in one ring section at a given position to emphasize the digital code, single openings of predetermined diameter would be sufficient. On the other hand, if desired, three or more openings could be used at various positions.

Disc 57 comprises two concentric channel-shaped rings 82 and 83. The outer ring 82 leads to the intake 86 for cylinder 53 and the inner ring 83 leads to the exhaust 87 of the cylinder 53.

In operation, on information received from the control 65 62, servomotor 58 will rotate shaft 59 to bring openings 71 and 72 of the distributor into line with any one of a series of positions 1 to 36, shown in FIG. 2. In the first position, opening 71 will be brought into line with opening 0-1 and opening 72 into line with 0-19. At this time, pressure drives fluid from source 67 through outer ring 63 of disc 54, through opening 0-1, through distributor opening 72, through outer ring 82 of disc 57 to the intake 86 to drive cylinder rod 52 to a predetermined position. Fluid returns from the exhaust 87, through inner ring 83 of disc 57 through opening 0-19 through distributor opening 71, through the inner ring 64 of disc 54 to the return 70 68. At positions 2 and 20 of distributor 55, there are no coded openings, and hence no motion of the piston rod 52. Further rotation of distributor 55 places its opening 72 in line with opening 0-3 and its opening 71 in line with opening 0-21. This movement enables pressure to be applied from the outer ring 63 through opening 72, through opening 0-3 through inner ring 83 to exhaust 87, to return the piston to the original position. Surplus fluid returns over intake 86, through ring 82, opening 0-21, opening 71 and ring 63 to storage.

The diameter of outlet opening 0-19 is shown slightly smaller than the diameter of the inlet opening 0-1 to a degree dependent on the inertia of the moving parts, e.g., it may take into consideration a slight overshooting of the desired piston rod position. The diameter of opening 0-3 slightly exceeds that of opening 0-1 to assure that the piston will return to the stop 84. Opening 0-21 is made larger than opening 0-3 to eliminate any back pressure. While the operation at only a few positions has been de-

scribed, it is obvious that the operation will be the same at corresponding positions.

The purpose of the larger return position openings 0-3-0-21; 0-6-0-24; 0-9-0-27; etc., is to preclude any false positioning of the cylinder rod, when the distributor disc is operated at relatively high speeds between positions. For example, if the distributor starts from position 36 and it is desired to rotate the distributor five positions forward to position 13, fractional amounts of fluid would pass through the system at positions 1, 4, 7 and 10, at the respective openings 0-1, 0-4, 0-7 and 0-10, if the intermediate return position openings 0-3-0-21, etc., were not provided. It is proper to consider these return positions as lending accuracy to the system at the cost of useful space on the coded disc 56.

In practice, disc space could be conserved by having the input and output portions of the distributor cover only single ring portions of the coded disc and reversals of the piston rod could be obtained by crossing holes in the coded disc. In this case, distributor 55' includes the 20 openings 71' and 72'. Opening 0-1', equivalent to 0-1, remains as previously described but, as shown in FIG. 4, opening 0-19' of disc 56' would be brought adjacent to opening 0-1'. Position 2, of course, would not be affected. Opening 0-3' would enter the control disc in the outer ring portion but leave through the inner ring portion and vice versa for opening 0-21', as shown in FIGS. 5 and 6. Corresponding openings at other positions would be arranged in a similar manner.

In a preferred mode of operation, position 36 may be considered as the home position of the distributor, the control apparatus directing the distributor to return to the home position after it has been moved to one of the operating positions. The necessary information could be provided, for example, on a punched card or tape.

Various changes may be devised without departing from the spirit of the invention.

What is claimed is:

1. A fluid distribution system comprising a fluid source, a fluid outlet, a coded member having a series of non-identically sized openings arranged therein in a predetermined manner, said opening sizes and the manner of arrangement thereof being determined in accordance with the amounts of fluid to be passed through the respective openings, a distributor having at least one passageway, means to effect relative movement between the coded member and the distributor to bring the passageway into alignment with one or more openings to pass a predetermined amount of fluid from the fluid source through the aligned opening or openings and the passageway to the fluid outlet.

2. A fluid distributor according to claim 1, wherein the coded member is a disc, and the distributor is a disc contiguous with the coded disc.

3. A fluid distribution system according to claim 2, including an inlet disc at one side of the rotary member, and an outlet disc at one side of the coded member, each having at least one fluid path.

4. A fluid distribution system according to claim 3, wherein the inlet and outlet discs each comprise a pair of concentric ring sections, one ring section supplying fluid through the distributor in one direction, the other ring section receiving fluid from the distributor in the opposite direction, and the coded disc being provided with at least a pair of openings at each of a series of positions about the disc.

5. A fluid distribution system according to claim 4, wherein the openings of a pair are at diametrically opposite positions on the coded disc.

6. A fluid distribution system according to claim 5, wherein one opening of a pair in at least one position is smaller than the other opening in the same position to allow for the inertia of moving parts.

7. A fluid distribution system according to claim 4, wherein there are two sets of openings on the disc, one set of openings representing operate positions and the other set of openings representing return positions, the operate openings and the return openings being alternately arranged about the coded disc member.

8. A fluid distribution system in accordance with claim 7, wherein the diameter of the openings in the return positions exceeds the diameter of the openings in the operate positions.

9. A fluid distribution system according to claim 7, wherein an opening in a return position is larger than another opening in the same return position to eliminate any back pressure.

10. A fluid distribution system according to claim 7, wherein the openings of the coded disc are at inner and outer positions and there are a pair of coded openings in each return position, in a given position the passageway of the distributor crossing over from the outer ring section of the inlet disc to the opening in an inner position, and the other passageway crossing over from an inner ring section of the inlet disc to the opening in the outer position.

11. A fluid distributor according to claim 2, including 25 a motor for effecting relative movement between the discs by driving one of the discs to a preselected position, and control apparatus for controlling the operation of said motor.

12. A fluid distribution system comprising in successive 30 contiguous relation an inlet disc, a disc distributor, a coded disc, and an outlet disc, the inlet disc comprising two concentric hollow ring sections, one ring section being connected to a source and the other ring section being connected to a fluid return, the distributor disc being rotatable and including two passageways, one for one ring section and the other for the other ring section, the coded disc including a series of openings arranged at different positions about the disc, there being at least a pair of openings for each position, one opening of a pair passing fluid 35 in one direction from the distributor disc and the other opening passing fluid in the opposite direction to the distributor disc, and the outlet disc comprising two concentric hollow ring sections, one leading to a fluid intake and the other leading to a fluid exhaust.

13. A fluid distribution system according to claim 12, including a piston cylinder operatively connected to the intake and exhaust.

14. A fluid distribution system according to claim 12, including a servomotor for driving the distributor to a predetermined position.

15. A fluid distribution system according to claim 12, wherein the distributor disc includes a pair of L-shaped openings, one opening being coupled to the outer hollow ring section of the inlet disc, and the other opening being coupled to the inner hollow ring section of the inlet disc.

16. A fluid distribution system according to claim 12, wherein the openings of the coded disc are at inner and outer positions, and there are a pair of openings, in a given position one passageway of the distributor extending between the outer ring section of the inlet disc and the outer opening, and the other passageway extending between the inner ring section of the inlet disc and the inner opening.
